UNITED STATES PATENT OFFICE.

WILLIAM A. WILLIAMS, OF BARTON, OHIO.

MINE-CHECK HOLDER.

1,182,953.

Specification of Letters Patent. Patented May 16, 1916.

Application filed April 20, 1914. Serial No. 833,188.

To all whom it may concern:

Be it known that I, WILLIAM A. WILLIAMS, a citizen of the United States of America, and resident of Barton, county of 5 Belmont, and State of Ohio, have invented certain new and useful Improvements in Mine-Check Holders, of which the following is a specification.

This invention relates broadly to mine- 10 check holders, and it has for its primary object to provide a check receptacle having mechanism by means of which a deposited check is retained against displacement until the car to which it is attached assumes a 15 predetermined inclination, as at the dumping point, whereupon it is automatically released.

A further object is to provide an automatic check holder the check holding and 20 releasing mechanism of which can not be actuated to release deposited checks by shocks due to collisions or bumping of cars.

With the above-recited main objects in view, the invention resides in the features 25 of construction, arrangement of parts and combinations of elements which will herein- after be fully described, reference being had to the accompanying drawings, forming a part of this specification, in which—

30 Figure 1 is a side elevation of a mine car occupying loading position, showing my check holder mounted thereon; Fig. 2 is a similar view showing the car occupying dumping position and showing the check 35 holder in check releasing position; Fig. 3 is an enlarged upper edge view of the check holder, detached; Fig. 4 is a section on the line 4—4, Fig. 3, showing the device in upright position with the mechanism in check- 40 holding position; and—Fig. 5 is a similar section showing the device inclined to substantially the position assumed when the car occupies dumping position and showing the mechanism in check-releasing position. Fig. 45 6 is a sectional view taken on the line 6—6, Fig. 4.

Referring to said drawings, in which like designating characters distinguish like parts throughout the several views, 1 indicates generally a casing, preferably formed of metal and made rectangular in shape. Said casing consists, preferably, of a back- 50 plate 2 and an interfitting box-like cover 3, the latter being removably attached to said back-plate, as by means of screws 4. Said casing is adapted for mounting in any suitable manner upon a side of a mine-car, as

5, whereon it occupies a substantially upright position, as shown in Figs. 1 and 2. Provided in the upper edge of said casing 60 is a check-receiving slot 6 which communicates with the upper end of a curved or inclined passage or runway 7 formed within a tube-like member 8 which is of substantially rectangular form in cross section. 65 The opposite, or lower, end of said member opens outward through the front edge of the casing and forms a spout through which checks may be discharged, as will herein- after be explained. Pivoted intermediate 70 its ends outside said runway is a lever 9 having fixed thereto or formed integral therewith at a point above its pivotal mounting a forwardly projecting arm 10 which, in the normal upright position of said lever, 75 stands projected into said runway through an opening 11 provided in the rear side of the tube-like member 8. In this position said arm constitutes a guard which so restricts the capacity of said runway as to 80 prevent the passage thereby of deposited checks 12, such checks being supported thereby, as shown in Fig. 4. A weight 13 carried upon the lower end of said lever 9 is designed to maintain the latter in upright 85 position irrespective of the position assumed by the casing within which it is mounted, thus maintaining the arm or guard 10 projected into the runway in a position preventing the passage thereby of checks 90 except when said casing occupies the sharply inclined position which is assumed only when car assumes dumping position.

In order to prevent free or unobstructed pendulum-like swinging movement of the 95 lever, which would result in the untimely release of deposited checks, I provide a suitable movement retarding device consisting of a small cylinder 14 in which operates a reciprocating piston 15, the latter being suitably connected to the free upper end of the lever 9, as by a pitman or connecting rod 16. Said piston may be fitted more or less loosely in the cylinder so that air may pass thereby in entering and exhausting from the 105 cylinder, in which case no port for the passage of air need be provided in said cylinder; or a small port may be provided in the cylinder, as shown at 17, Fig. 5, if desired. In either case, however, the passage for air 110 must be so restricted that the air will be permitted to exhaust but slowly from the cylinder, offering such resistance to the inward movement of the piston as will effec-

tually prevent the lever 9 from swinging to check-releasing position under the actuating influence of sudden shocks or jars, due to collisions and the like, communicated to the 5 mechanism.

A suitable hinged cover, as 18, may be provided on the casing to overlie the slot 6 for excluding dust and foreign matter. A light-weight swinging closure 19 may be 10 provided in the lower end of the runway, the lower or free end of which normally seats against a shoulder 20 provided in the bottom of said runway. While not obstructing or impeding the discharge of a released 15 check, said closure prevents tampering with the check-holding mechanism from the lower end of said runway, as by the insertion of a wire or other instrument.

From the foregoing it will be seen that 20 checks are positively retained in my device until the car to which it is attached assumes a certain inclination. The checks are preferably ejected into a receptacle, chute, or the like (not shown) located at a suitable point 25 on the dumping tipple.

What is claimed is—

1. In combination with a mine-car, a check holder mounted on the car, said holder comprising a suitable inclosure having a 30 passageway for checks therethrough, a guard movable into and out of said passageway normally maintaining the latter closed against the passage of checks therethrough, means whereby said guard is automatically 35 withdrawn when the car assumes a predetermined position, and means limiting the rapidity of said withdrawal.

2. In combination with a mine-car, a check holder mounted on the car, said holder 40 comprising a suitable inclosure having a passageway for checks therethrough, a guard supported outside said passageway and movable into and out of the latter, means normally maintaining said guard 45 projected into said passageway for closing the latter against the passage of checks therethrough, said means automatically effecting the withdrawal of said guard only when said car assumes a predetermined 50 inclination.

3. In combination with a mine-car, a check holder mounted on the car, said holder comprising a suitable inclosure having a 55 passageway for checks therethrough, a lever pivoted outside said passageway, a guard carried by said lever and adapted to move into and out of said passageway with the swinging movement of said lever, gravity controlled means normally holding said lever 60 in a position wherein said guard is projected into said passageway for closing the latter against the passage of checks therethrough, said means being adapted to effect

the withdrawal of said guard when said car assumes a predetermined inclination, and 65 means limiting the rapidity of such withdrawal.

4. In combination with a mine-car, a check holder mounted on the car, said holder comprising a suitable inclosure having a 70 passageway for checks therethrough, a pivoted lever located outside said passageway and carrying a guard which is movable into and out of said passageway with movement of said lever, gravity controlled means 75 normally maintaining said lever in upright position with said guard projected into passage-closing position, said means being adapted to swing said lever to guard-withdrawing position when the car assumes a 80 predetermined inclination, and means connected to said lever whereby movement of the latter to guard-withdrawing position is retarded.

5. In combination with a mine-car, a 85 check holder mounted on the car, said holder comprising a suitable inclosure having a passageway for checks therethrough, a guard normally disposed within and withdrawable from said passageway, said guard 90 being designed to normally maintain said passageway closed against the passage of checks therethrough, a pivoted lever mounted outside said passageway by which said guard is carried, a weight carried by the 95 lower end of said lever for normally maintaining the latter in a position holding the guard in passage-closing position, and means limiting the rapidity of guard-withdrawing movement of said lever. 100

6. In combination with a mine-car, a check holder mounted on the car, said holder comprising a suitable inclosure having a passageway for checks therethrough, a guard movable into and withdrawable from 105 said passageway, said guard being normally disposed within said passageway for maintaining the latter closed against the passage of checks therethrough, a pivoted lever mounted outside said passageway by which 110 said guard is carried, a weight carried by the lower end of said lever for normally maintaining the latter in a position holding the guard in passage-closing position, and means limiting the rapidity of guard-withdrawing movement of said lever. 115

In testimony whereof, I affix my signature 120 in presence of two subscribing witnesses.

WILLIAM A. WILLIAMS.
